UNITED STATES PATENT OFFICE.

FRANK KNUPFER, OF DETROIT, MICHIGAN.

COLLAPSIBLE-TUBE-FINISHING MACHINE.

1,076,985.

Specification of Letters Patent.

Patented Oct. 28, 1913.

Application filed December 23, 1912. Serial No. 738,172.

To all whom it may concern:

Be it known that I, FRANK KNUPFER, a citizen of the United States of America, residing at Detroit, in the county of Wayne 5 and State of Michigan, have invented certain new and useful Improvements in Collapsible-Tube-Finishing Machines, of which the following is a specification, reference being had therein to the accompanying 10 drawings.

This invention relates to a screwthreading machine adapted to finish the nipples of collapsible tubes, such as are commonly used for pigments and paste of various sorts and 15 includes means whereby the tube is suitably supported throughout the operation, is rapidly and efficiently operated upon and is finished without the necessity of remounting.

20 The invention consists in the matters hereinafter set forth and pointed out in the appended claims.

In the drawings:—Figure 1 is a view in side elevation, partially broken away of 25 mechanism that embodies features of the invention; Fig. 2 is a view of the driving end of the machine; Fig. 3 is a view in elevation of the other end of the machine; Fig. 4 is a plan view in detail and enlarged of the 30 machine, parts being broken away; Fig. 5 is a view in section on line V—V of Fig. 1; Fig. 6 is a view in section on line VI—VI of Fig. 1 with parts omitted; Fig. 7 is a view in detail of a tube blank to be operated upon; and Fig. 8 is a sectional view showing the finished nipple of the tube.

A main frame 1 of suitable material and design to combine strength with lightness provides a bearing for a head 2 rotatable 40 on a horizontal axis in which shafts 3 are independently rotatable, the shafts being disposed in a circle concentric with the axis of rotation of the head. Spindles 4, with appropriate tapered socket connections with 45 the inner end portions of the shafts 3, project from the head a sufficient distance to be brought successively into operative relation to trimming and threading means. The spindles 4 have screwthreaded nipples 5 so 50 that when tube blanks, as indicated at 7, are thrust thereon the rotation of the nipple causes the latter to work its way into a suitable recess or opening in the blank nipple 6 so that the latter is thereafter driven by 55 the spindle. A carriage 8 is longitudinally reciprocated on a suitable guide portion of

the frame 1 in substantially axial alinement with the head 2 by means of a friction roller 9 that travels in a cam groove of a suitable cam 10. The latter is driven by means of 60 a shaft 12 journaled in the main frame. A tool post 13 on the carriage carries a suitable boring and finishing tool 14 so as to be in axial alinement with each spindle as the latter are brought successively in register 65 therewith. Suitable provision is made for accurate adjustment of the carriage in the tool post.

Means for threading the nipples of the blanks consists of a pair of die wheels 15 each journaled in the end of a rock arm 16 and driven in similar directions by means of a gear train indicated at 17. The wheels are normally held apart by a suitably disposed spring 18 so that the nipple ends of 70 the blanks may pass freely between them. Whenever a spindle is in register with or in proper operative relation to and between the wheels 15 and is momentarily arrested by suitable mechanism as herein described, 75 the forward movement of the carriage 8 forces a spreading finger 19 between the end portions of the rock arms 16 and thereby brings the die wheels 15 into rolling contact with a blank nipple. Proper adjustment of the arms as to their relative movement is obtained by suitable screwthreaded stops 20 with check nuts 21, the driving 80 mechanism and pivotal support of the arms being carried by a bracket 22 that is longitudinally movable on the frame for obtaining adjustment in either direction.

A cutting off disk 23 on the end of a lever arm 24 is yieldingly pressed by a spring 25 or other like means against the body of the 95 blank on the spindle to trim the same, the arm 24 being pivoted on a bracket 26 that is adjustable longitudinally of the frame on a suitable guide-way 27. A presser roll 28 encounters the blank above the disk and 100 holds it firmly in position, being yieldingly forced toward the spindle by the action of the spring 29 on a bell crank 30 on which the presser roll 28 is journaled, the bell crank being fulcrumed on the cutter disk 105 arm 24.

A main shaft 31 is journaled in the main frame and is operatively connected as by a belt 32 with a counter shaft 33. A reduction gear train 34 drives the cam shaft 12. 110 A mangled gear 35 on the shaft 12 intermittently turns the head 2 by means of a

mangled pinion 36 with which it meshes, the point of inaction between the mangled gear and pinion being coincident with the registration of one spindle with the cutting off and trimming tool and the adjacent spindle with the screwthreaded and trimming means. Positive stoppage of the head 2 at the desired point is obtained by means of a detent lever 37 whose outer end drops into 10 suitably disposed notches 38 in an end plate of the head, the other end of the detent carrying a friction roll 39 that travels on and is oscillated by a cam 40 on the shaft 12.

The spindles 4 and their corresponding 15 shafts are conveniently driven by means of a belt 42 passing around a pulley 43 on the main shaft 31 and around counter pulleys 43 on the ends of the respective spindle shafts. During the time that the rotation 20 of the head has carried one of the spindle counter pulleys out of contact with the driving belt 42, the counter pulley thereon is frictionally rotated by a roll 44 in the opposite direction to the rotation of the spindles 25 driven by the belt 42, the roll 44 being keyed to a shaft 45 that is connected by a gear train 46 or the like to a shaft 47. The latter is rotated by the belt 42 through contact with an idler and tightener 48, a companion 30 49 to the latter holding the belt 42 in proper relation to the spindle counter pulleys. As a result of this operation the head of the machine intermittently rotates in one direction bringing the spindles successively into 35 registration with the trimming and screw threading tools and at one point in the revolution of each spindle reversing the direction of the rotation of the latter.

In use, a blank as for example the one indicated at 50 in Fig. 4, is thrust on to the 40 spindle at this position and the screw nipple of the spindle causes the tube blank to rotate. This blank is then successively brought to the positions indicated by the blank 51 and the blank 52 in Fig. 4. When the blank 45 leaves the last position, the spindle with which it is in screwthreaded engagement moves into a position where it is rotated momentarily in a reverse direction so that 50 when the operator places his hand upon the blank and arrests it, the screwthreaded nipple of the spindle runs the blank off. The operator then withdraws it entirely, free from the machine.

55 As herein shown there are four spindles and four positions assumed by them, first, the one in which the blank is forced into engagement with the spindle, second, the position where the trimming and boring tool 60 is applied, third, the position where the screwthreads are spun on to the nipple by the die wheels and the other end of the tube trimmed, and fourth, the position where the reverse rotation of the spindle causes 65 the blank to be unscrewed from the nipple.

and leaves the blank clear to be drawn off by the operator.

The machine is simple in construction and effective in operation and as the motion is substantially continuous it brings the blanks 70 up to the tools in succession at a speed limited only by the capacity of the person feeding the machine, and finishes the blank before it leaves the machine.

Obviously, changes in the details of construction 75 may be made without departing from the spirit of my invention and I do not care to limit myself to any particular form or arrangement of parts.

What I claim is:

1. A collapsible-tube finishing machine comprising a rotatable head, tube blank receiving members journaled therein each adapted to rotate an applied blank in one direction and to release such blank when the 85 direction of rotation is reversed, cutting off, finishing and screwthreading means with which the receiving members are brought successively into register, and means for operating the head, the members and the several means in timed relation adapted to reverse the direction of each receiving member once in each revolution of the head.

2. A collapsible-tube finishing machine comprising a main frame, a head rotatable 95 therein, tube blank receiving members journaled in the head and adapted to revolve around its center of motion, each member being adapted to rotate an applied blank in one direction and to release such blank when 100 the direction of rotation is reversed, means for rotating the receiving members in the head adapted to reverse the direction of rotation of each receiving member once during each revolution of the head, nipple 105 finishing means, nipple screw threading means and cutting-off means with which the receiving members are brought successively into operative relation during each revolution of the head and mechanism for operating the parts in timed relation.

3. In a collapsible tube finishing machine, a main frame, a head rotatable therein, tube blank receiving members journaled in the head and adapted to revolve with the head 115 around its center of motion, each member being provided with means to rotate an applied blank in one direction and to release such blank from the member when the direction of rotation is reversed, means for rotating the members adapted to reverse the direction of rotation of each member once during each revolution of the head, and means for operating the parts in timed relation.

4. A collapsible-tube finishing machine comprising a main frame, a head rotatable 120 therein, tube-blank receiving members journaled in the head and adapted to revolve therewith around its center of motion, finish- 130

- ing means, screwthreading means and cutting off means with which each receiving member is brought successively into operative relation during each revolution of the head, means for intermittently arresting the head when the members are in such operative relation, means for rotating the receiving members adapted to reverse the direction of each receiving member during one period of arrest in each revolution of the head, and mechanism for operating the several parts in timed relation.
5. A collapsible-tube finishing machine comprising a main frame, a head horizontally journaled therein, tube blank receiving members journaled in the head and adapted to rotate an applied blank in one direction and to release such blank when the direction of rotation is reversed, means for rotating the head, means for rotating the receiving members adapted to reverse the direction of rotation of each once during each revolution of the head, finishing means reciprocable in the main frame adapted to be brought into operative relation with the receiving members successively, screwthreading and cutting off means on the main frame with which the receiving members are brought successively into register during each revolution of the head, means for arresting the head intermittently as the members register with the finishing and screwthreading means successively and mechanism for operating the parts in timed relation.
- 35 6. In a collapsible tube finishing machine, a rotatable head, tube blank receiving spindles journaled in the head and adapted to revolve around the latter's center of motion, means for periodically arresting the head, means for rotating the spindles adapted to reverse direction of rotation of each spindle at one period of arrest during each revolution of the head, and a series of tube blank finishing means with which the spindles move successively into operative relation, the reversal of each spindle occurring when the latter is clear of such finishing means.
7. In a collapsible-tube finishing machine, a rotatable head, tube blank receiving spindles journaled in the head and arranged to revolve around the latter's center of motion, means for rotating the spindles adapted to reverse the direction of rotation of each once during each revolution of the head, each spindle being arranged to retain a tube blank thereon and to release said blank and permit its withdrawal from the spindle when the latter is reversely rotated.
- 55 8. A collapsible-tube finishing machine, comprising a main frame, a head horizontally journaled therein, a series of spindles concentric with the axis of rotation of the head each journaled therein and each provided with a screwthreaded nipple adapted to retain and drive a blank in one direction and to run a blank off against external resistance when turned in the other direction, mechanism for rotating the head, and mechanism for rotating the spindles adapted to reverse the direction of each spindle once during each revolution of the head.
- 15 9. A collapsible-tube finishing machine, comprising a main frame, a head horizontally journaled therein, a series of spindles concentric with the axis of rotation of the head each journaled therein and each provided with a screwthreaded nipple adapted to retain and drive a blank in one direction and to run a blank off against external resistance when turned in the other direction, mechanism for rotating the head, mechanism for rotating the spindles adapted to reverse the direction of each spindle once during each revolution of the head, and means for intermittently arresting the head at the moment of reversal of rotation of a spindle.
- 20 10. A collapsible-tube finishing machine, comprising a main frame, a head horizontally journaled therein, a series of spindles concentric with the axis of rotation of the head each journaled therein and each provided with a screwthreaded nipple adapted to retain and drive a blank in one direction and to run a blank off against external resistance when turned in the other direction, mechanism for rotating the head, mechanism for rotating the spindles adapted to reverse the direction of each spindle once during each revolution of the head, means for intermittently arresting the head at the moment of reversal of rotation of a spindle.
- 25 11. A collapsible-tube finishing machine, comprising a main frame, a rotatable head horizontally journaled therein, tube receiving spindles journaled in the head and adapted to revolve therewith around the latter's axis of motion, mechanism for rotating the spindles adapted to reverse direction of rotation of each once during each revolution of the head, means for momentarily arresting the head at the moment of reversal of rotation of the spindle, finishing means reciprocable on the main frame to and from the head adapted to be brought into operative relation to a spindle at each moment of arrest of the head, and screwthreading and cutting off means adapted to be brought into operative relation with a spindle during each moment of arrest.
- 30 12. A collapsible-tube finishing machine comprising a main frame, a rotatable head horizontally journaled therein, tube receiving spindles journaled in the head and adapted to revolve therewith around the latter's axis of motion, mechanism for rotating the spindles adapted to reverse direction of rotation of each once during each revolution of the head, means for momentarily arresting the head at the moment of reversal of rotation of the spindle, finishing means reciprocable on the main frame to and from the head, means adapted to reciprocate the finishing means and to hold the latter in operative relation to a spindle during the moment of arrest of the head, screwthreading means on the main frame, means for rotating the screwthreading means when the latter registers with a spindle, and cutting off means with which the spindles register successively.

12. A collapsible-tube finishing machine comprising a main frame, a head horizontally journaled therein, tube blank receiving spindles journaled in the head and adapted to revolve around the latter's axis of motion, means for rotating the spindles, means for intermittently arresting the head, finishing means reciprocable to and from the head with which each spindle is adapted to register during one period of arrest in each revolution of the head, screwthreading means with which each spindle is adapted to register once at a period of arrest during each

revolution of the head, means controlled by the reciprocating and finishing means for closing the screwthreading mechanism upon a blank, and cutting off means operating upon a blank coincidentally with the screwthreading means.

In testimony whereof I affix my signature 20 in presence of two witnesses.

FRANK KNUPFER.
